UNITED STATES PATENT OFFICE.

JOHN WEST, OF CHICAGO, ILLINOIS, ASSIGNOR TO THE UNION TYPE
FOUNDRY, OF SAME PLACE.

DESIGN FOR TYPE.

SPECIFICATION forming part of Design No. 18,516, dated August 7, 1888.

Application filed May 18, 1888. Serial No. 274,318. Term of patent 7 years.

To all whom it may concern:

Be it known that I, JOHN WEST, a citizen of the United States, residing at Chicago, county of Cook, State of Illinois, have invented and produced a new and original Design for a Font of Printing-Type, of which the following is a specification, reference being had to the accompanying typographic print, forming part thereof.

10 My design consists of a font of printing-type composed of capitals the characteristic feature of which is the light unshaded lines with terminal flourish in places, and dollar-marks, figures, punctuation-marks, &c., of
15 same style.

The letters A, N, and Y are shown in two

styles—the ordinary plain style and with the light line terminating with a flourish with terminal dot. B, P, and R have a short central terminal flourish. C, G, S, Z, \$, 2, 3, 5, 6, 7, 20 and ? have a descending tapering flourish. E, F, L, T, and Z are "old style," having slanting shade lines or points. &, \$, 3, and 5 have lower terminal flourish with a dot.

What I claim, and desire to secure by Letters Patent, is—

The design for a font of printing-type, substantially as herein shown and described.

JOHN WEST.
